(57) **CLAIM**

The ornamental design for a basketball cane tip, as shown and described.

DESCRIPTION

FIG. 1 is a perspective view of a basketball cane tip of the new design;

FIG. 2 is a front elevational view thereof;

FIG. 3 is a rear elevational view thereof;

FIG. 4 is a left side view, with the right side view being a mirror image thereof;

FIG. 5 is a top plan view thereof; and,

FIG. 6 is a bottom plan view thereof.

The broken lines depict portions of the article that form no part of the claimed design.

1 Claim, 4 Drawing Sheets
